UNITED STATES PATENT OFFICE

127,710

DESIGN FOR A CIGARETTE HOLDER

Clement Deitch, Port Angeles, Wash.

Application March 28, 1941, Serial No. 99,977

Term of patent 7 years

To all whom it may concern:

Be it known that I, Clement Deitch, a citizen of the United States, residing at Port Angeles, in the county of Clallam and State of Washington, have invented a new, original, and ornamental Design for a Cigarette Holder, of which the following is a specification, reference being had to the accompanying drawing, forming part thereof.

Figure 1 is a side elevational view of a cigarette holder with the slide valve of the tray part thereof in a retracted position, and showing my new design.

Figure 4 is an end elevational view viewing the cigarette holder from the terminal of the mouth-piece thereof, and

Figure 5 is an end view of the cigarette holder viewing the same from the extremity of the tray part thereof.

I claim:

The ornamental design for a cigarette holder, as shown.

CLEMENT DEITCH.
